(57) **CLAIM**

The ornamental design for an array microphone assembly, as shown and described.

DESCRIPTION

FIG. 1 is a front perspective view of the array microphone assembly in accordance with the present invention;

FIG. 2 is a rear perspective view thereof;

FIG. 3 is a front plan view thereof;

FIG. 4 is a rear plan view thereof;

FIG. 5 is a first side elevation view thereof;

FIG. 6 is a second side elevation view thereof, opposite from the first side elevation view; and,

FIG. 7 is a third side elevation view thereof.

The broken lines in the drawings illustrate the portions of the design that form no part of the claim.
